UNITED STATES PATENT OFFICE.

HERBERT A. AUSTIN, OF WORCESTER, MASSACHUSETTS. ASSIGNOR TO AMERICAN NARROW FABRIC COMPANY, OF WORCESTER, MASSACHUSETTS, A CORPORATION OF MASSACHUSETTS.

DESIGN FOR A DISPLAY CARTON.

Application filed March 25, 1926. Serial No. 17,052. Term of patent 14 years.

To all whom it may concern:

Be it known that I, HERBERT A. AUSTIN, a citizen of the United States, residing at Worcester, in the county of Worcester and State of Massachusetts, have invented a new, original, and ornamental Design for a Display Carton, of which the following is a specification, reference being had to the accompanying drawing, forming part thereof.

The figure is a perspective view of a display carton showing my new design.

I claim:

The ornamental design for a display carton, as shown.

HERBERT A. AUSTIN.
